UNITED STATES PATENT OFFICE

162,189

CHILD'S SHOE OR THE LIKE

Herman C. Levy, Coopersburg, Pa.

Application May 3, 1950, Serial No. 9,676

Term of patent 7 years

(Cl. D7—7)

To all whom it may concern:

Be it known that I, Herman C. Levy, a citizen of the United States of America, residing in Coopersburg, county of Lehigh, and State of Penna., have invented a new, original, and ornamental Design for a Child's Shoe or the like, of which the following is a specification, reference being had to the accompanying drawing, forming part thereof.

The figure is a perspective view of a child's shoe or the like, showing my new design.

The essential features of my design for a child's shoe reside in the one piece upper which is integral in the back and the two ends forming a seam on the toe portion thereof, in combination with a fastening means as shown and a binding at the top of the shoe of a color contrasting to the sides of the same, all as illustrated.

I claim:

The ornamental design for a child's shoe or the like, substantially as shown and described.
HERMAN C. LEVY.
